(57) CLAIM

I claim the ornamental design for a ribbon cartridge for a photo printer, as shown and described.

DESCRIPTION

FIG. 1 is a perspective view of a ribbon cartridge for a photo printer in accordance with the new design, a protruding pin being positioned on a housing of the ribbon cartridge for holding the ribbon cartridge;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
